SELF-CENTERING UNCOILER

Edwin T. Lorig, Ross Township, Allegheny County, Pa., assignor to United States Steel Corporation, a corporation of New Jersey

Application December 14, 1950, Serial No. 200,853

5 Claims. (Cl. 242—78)

1

This invention relates to an uncoiler for uncoiling coils of steel strip and more particularly to an uncoiler of the mandrel type. In this type of uncoiler the coil is mounted on a mandrel which extends through the center thereof and the strip is pulled therefrom and fed to processing equipment. As the coil unwinds there is a tendency for it to work from side to side and therefore guides have been provided to prevent excessive movement. These guides are expensive and cause damage to the edges of the strip. There also is danger that small pieces of metal will be torn from the edges of the strip and will get between the convolutions of the coil when the strip is recoiled, thus causing further damage to the strip in subsequent operations.

It is an object of my invention to provide an uncoiler of the mandrel type in which the coil is maintained in centered position as the strip is unwound.

This and other objects will be more apparent after referring to the following specification and attached drawings, in which:

Figure 1 is a sectional view showing a coil supported on the mandrel of my invention;

Figure 2 is a sectional view taken on the line II—II of Figure 1;

Figure 3 is a view taken on the line III—III of Figure 1 with the coil of strip removed therefrom;

Figure 4 is a view of a modification, similar to Figure 1, showing a two part mandrel with one part in retracted position and the other part in forward position;

Figure 5 is a sectional view taken on the line V—V of Figure 6; and

Figure 6 is a view of the mandrel of Figure 3 showing the parts thereof in interlocked position and supporting a coil of strip.

Referring more particularly to Figures 1, 2 and 3 of the drawings, the reference numeral 2 indicates a reciprocating carriage for supporting a mandrel shaft 4. The carriage 2 is mounted for reciprocation on a track 6. A supporting block 8 is mounted on the end of the mandrel shaft 4 remote from the carriage 2 and a second supporting block 10 is mounted on the shaft 4 intermediate the ends thereof. The housing is provided with aligned spaced apart bearings 12 and 14 for the supports 8 and 10, respectively. A guide 15 is provided for supporting block 10 between the carriage 2 and bearing 14. The shaft 4 is provided with a V-shaped bent portion 16 between the supports 8 and 10. The legs of the V extend slightly downwardly toward each other as best shown in Figure 1. A pair of frusto-conical rolls 55

2

18 and 20 are rotatably mounted on the legs of the bent portion 16. For this purpose, roller bearings 22 are provided on the shaft 4. The rolls 18 and 20 are frusto-conical in shape with their large diameter ends being adjacent each other. The rolls are slightly spaced from each other and are provided with gears 24 on their adjacent ends so that the rolls must rotate in synchronism. The frusto-conical rolls 18 and 20 form a self-centering roll of the type shown in my copending application, Serial No. 97,218, filed June 4, 1949, now Patent No. 2,593,157, dated April 15, 1952. The top of the rolls 18 and 20 are in substantial alignment to receive a coil of strip S. Other self-centering rolls of the type shown in my copending applications, Serial No. 138,389, filed January 13, 1950, now Patent No. 2,592,581, dated April 15, 1952, and Serial No. 145,648, filed February 23, 1950, now Patent No. 2,593,158, dated April 15, 1952, may be substituted for the self-centering rolls of the type shown. The strip S is pulled from the mandrel beneath an idler roll 26 and over a second idler roll 28 to the processing equipment. The mandrel, functioning as a self-centering roll, will prevent the coil of strip S from moving axially. After the coil is unwound the carriage 2 is retracted to a position where the supporting block 10 rests on the guide 15 and the block 8 rests in the bearing 14. A new coil is then brought into position and the carriage 2 is moved to the position shown in Figure 1.

In the second embodiment of my invention shown in Figures 4, 5 and 6, two mandrel shafts 30 and 32 are mounted on carriages 34. Only the left hand carriage is shown, it being understood that the right hand carriage is the same as the one shown. Each of the carriages is mounted for movement on a trackway 36. Mounted on the shafts 30 and 32 intermediate the ends thereof are supporting blocks 38 and 40, respectively. The uncoiler housing is provided with spaced apart aligned bearings 42 and 44 for receiving the supporting blocks 38 and 40, respectively. The ends of the shafts 30 and 32 are provided with reduced end portions 46 and 48, respectively, with the axes thereof being bent slightly downwardly. The portion 46 is provided with a frusto-conical male member 50 which is received in a similarly shaped female portion 52 in the end of the reduced portion 48. Frusto-conical rolls 54 and 56 are mounted on the reduced portions 46 and 48 with their large diameter ends adjacent each other. The rolls 54 and 56 are mounted for rotation on bearings 58 and 60, respectively. The rolls 54 and 56 are held in place by means of nuts 62 and 64 threaded on the shafts 30 and 32,

respectively. The ends of the rolls 54 and 56 are provided with gear teeth 66 for connecting the rolls for synchronous rotary movement when they are in their inner position as shown in Figure 6. Guideways 67 are provided adjacent the bearings 42 and 44 for receiving the supporting blocks 38 and 40.

In this embodiment of my invention the coil of strip S is unwound in the same manner as in the first embodiment. When it is desired to place a coil of strip S on the mandrel, the carriages 34 are retracted until the roll 56 is in the position shown in Figure 4 with the supporting block 40 resting on the guideway 67 and the roll 54 is retracted to a similar position. A coil is placed in position and the carriages 34 are moved toward each other until the supports 38 and 40 are received in the bearings 42 and 44, respectively. As shown in Figure 6, the male and female connections 50 and 52 act to center the rolls 54 and 56 and hold them in stable relationship while the coil is being unwound.

The operation of the device is the same as that of my first embodiment and other types of self-centering rolls may be substituted for that shown.

While several embodiments of my invention have been shown and described it will be apparent that other adaptations and modifications may be made without departing from the scope of the following claims.

I claim:

1. An uncoiler comprising a pair of frusto-conical rolls arranged with their large diameter ends adjacent each other, said rolls being arranged with their axes of rotation converging slightly downwardly toward each other, and means connecting said rolls for positive synchronous rotary movement.

2. An uncoiler comprising a stationary substantially horizontal bent shaft, a pair of frusto-conical rolls rotatably mounted on said shaft with their large diameter ends being adjacent each other, said rolls being arranged with their axes of rotation converging slightly downwardly toward each other, and means connecting said rolls for positive synchronous rotary movement.

3. An uncoiler comprising a pair of substan-

tially horizontal shafts mounted for movement toward and away from each other, a frusto-conical roll mounted on each shaft with their large diameter ends being adjacent each other, said rolls being arranged with their axes of rotation converging slightly downwardly toward each other, and means connecting said rolls for positive synchronous rotary movement when they are in their inner position.

10. 4. An uncoiler comprising a pair of substantially horizontal shafts mounted for movement toward and away from each other, a frusto-conical roll mounted on each shaft with their large diameter ends being adjacent each other, said rolls being arranged with their axes of rotation converging slightly downwardly toward each other, a male and female connection between the ends of said shafts, and means connecting said rolls for positive synchronous rotary movement when they are in their inner position.

15. 5. An uncoiler comprising a stationary substantially horizontal shaft having a bent portion thereon, a pair of frusto-conical rolls rotatably mounted on the bent portion of said shaft with their large diameter ends being adjacent each other, said rolls being arranged with their axes of rotation converging slightly downwardly toward each other, means connecting said rolls for positive synchronous rotary movement, a housing, 20 spaced apart bearings in said housing, a support on said shaft on each side of said bent portion, said supports being received in said bearings when the uncoiler is in operative position, and means for reciprocating said shaft.
